UNITED STATES PATENT OFFICE.

HENRY B. DAVIES, OF TOLEDO, OHIO, ASSIGNEE, BY MESNE ASSIGNMENTS, TO THE ELECTRIC AUTO-LITE COMPANY, OF TOLEDO, OHIO, A CORPORATION OF OHIO.

ELECTRICAL SYSTEM.

Application filed February 13, 1918, Serial No. 216,856. Renewed May 10, 1921. Serial No. 468,249.

This invention relates to electrical systems containing a plurality of circuits each of which is electrically associated or connected with the other circuit or circuits.

In general terms, the invention is comprehended in the utilization, in conjunction with a given circuit or circuits of a modifying or control circuit which is preferably, although not necessarily independent of the other circuits and which has an inductive influence on said circuits to control the current flow and other electrical conditions of the other circuits. Preferably, the invention is embodied in a short circuited coil wound inductively, the total capacitance of the circuit being appreciably less than that of the other circuits and combining with the inductance of the coil to give a natural period of oscillation to the circuit less than that of the other circuits. This coil is placed in inductive relation to a portion of the circuit, the current or other electrical characteristics of which is to be modified, the coil operating to suppress or modify the current, in the other circuits having currents therein oscillating at frequencies below the natural period, as determined by its inductance and capacitance, of the control coil.

More specifically the invention relates to an electric circuit having utility in connection with ignition system for automobiles.

In electrical circuits in which oscillating currents flow, it is advantageous at times to suppress or diminish currents of a certain frequency without, at the same time, hindering or modifying circuits of other frequencies. In ignition systems for automobiles, for example, in order to have sufficient current for the higher speeds of operation of the system, it is desirable that the conductive resistance of the circuit be diminished to a point where the current available at the highest speed is adequate. This decrease in resistance, however, would permit currents of too high value to flow at the lower frequencies which might cause injury to the circuits; and to offset this condition, means should be provided for automatically suppressing or hindering the current flow at the lower frequencies.

It is an object, therefore, of the present invention to provide a means for electrical circuits which is effective at lower frequencies only to reduce the current flow in the circuits. It is another object of the invention

to provide automatic control means for alternating currents flowing in an electrical circuit which is operative only at or below a given frequency of alternation. Still another object of the invention is to provide a new and improved form of ignition for internal combustion engines, which is suitable, and responsive to modern requirements.

Another object of the invention is to provide a type of ignition which automatically compensates for the increased inductive effects of the circuit at high speeds, thereby maintaining an approximately even current value in the secondary spark plug circuit through wide variations of engine speed.

Further objects, and objects relating to economies of manufacture and details of construction will definitely appear from the detailed description to follow.

A structure and arrangement constituting an embodiment of my invention which may be preferred is illustrated in connection with an ignition system in the accompanying drawings, forming a part of my invention in which

Fig. I is a diagrammatic view of an ignition system and apparatus embodying my invention;

Fig. II is a detail view of a form of winding for the ignition coil;

Fig. III is a modified arrangement of the ignition coil; and

Fig. IV shows a second modification of the ignition coil.

In the drawings, similar numerals refer to similar parts throughout the several views.

In the ignition system illustrated diagrammatically in Fig. I, the numeral 1 designates an electric generator adapted to charge a storage battery 2, and furnish current for the ignition circuit. The generator is of the regulated type and is here shown as a "third brush" generator having a shunt field 3, connected to a main brush 4, and a third auxiliary brush 5. Intermediate the storage battery which is connected across the mains in parallel with the load 6, and the generator 1, is a reverse current cut-out with the usual shunt coil 7, series coil 8, core 9, armature 10, and contacts 11 and 12. A switch 13 is placed in the load circuit.

The ignition circuit comprises the interrupter 14, rotatable cam 15, condenser 15' connected in parallel with the interrupter, switch 16, and primary induction coil wind-

ing 17. The secondary winding 18 is grounded at one end and at its other end is connected to the distributor arm 19, through which connections to the various spark plug circuits 20, 21, 22 and 23 are made. A choke coil comprising a short-circuited winding 24 is associated with the windings 17 and 18.

Various methods of applying the different windings may be employed, the results obtained being similar. In the method illustrated in Fig. II, the three windings are wound on a common core, which effects a greater economy in metal and decreases the inductive lag at high frequencies. In Fig. III a closed magnetic circuit 25 is shown, with the choke coil 24 separated from the induction coil proper; and in Fig. IV a similar closed magnetic circuit 26 is shown, with the primary and secondary separated to different portions of the circuit, and the choke coil 24 placed adjacent to the primary winding. Instead of employing a closed magnetic circuit as shown in Figures III and IV, a partly closed circuit, or a circuit in which a portion has small cross-sectional area, may be used.

In ignition systems where the source of current is maintained at approximately constant potential, as in the battery system, a serious difficulty in the ignition at high frequencies arises due to the inductive lag and consequent decrease in effective current in the primary at the break of the interrupter contacts. To design the ignition coil for the obtainable high speed currents without additional controlling devices, would be impracticable as at low frequencies serious heating effects would result. To avoid this difficulty, I have provided a choke coil with a determined time constant such that at low speeds the primary current is effectively cut down. At the higher speeds, however, the choke coil gradually becomes ineffective at the instant of break, thereby permitting normal operation of the induction coil. It is obvious that the time constant of the choke coil should be greater than that of the primary coil to permit the above action. In this way, the ignition coil may be designed to give an effective spark plug current at the higher frequencies of operation, thus greatly increasing the efficiency of the ignition system.

The invention has been described specifi-

cally in relation to ignition circuits, but it is obvious that the tertiary coil may be as readily applied to other circuits wherein it is desirable that lower frequency electrical alternations or oscillations be suppressed or modified, either to obtain closer control of current in a second circuit or for other reasons. It is obvious also, that while interruptions of the primary circuit are indicated in relation to the ignition system specifically described, the control coil is equally effective as a control medium, irrespective of the means by which the alternations of the primary circuit are produced. Attention is further directed to the fact that while there are three circuits shown all physically disconnected, such disconnection is not essential for the utilization of the invention, the requisite being that the circuits be conductively related.

I am aware that the various embodiments of my invention as here shown and described, are susceptible of considerable variation without departing from the spirit of my invention, and, therefore, I desire to claim the same broadly as well as specifically, as indicated by the appended claims.

Having thus described my invention, what I claim as new, and desire to secure by Letters Patent, is:—

1. In an ignition system, the combination of the primary circuit adapted to convey a periodically varying current, a secondary circuit inductively related thereto and means including an independent tertiary circuit magnetically in series with the primary circuit for maintaining an approximately constant induced electromotive force in said secondary circuit depending upon the frequency of the variations.

2. In an electrical system, the combination of a primary winding, a secondary winding inductively related thereto and a short circuited tertiary winding inductively related to said windings and positioned adjacent said windings and magnetically in series relationship with said windings to diminish the current induced in said secondary winding at low speeds, depending upon the frequency of the primary current.

In testimony whereof, I affix my signature.

HENRY R. DAVIES.
